United States Patent

Des. 234,386
Patented Feb. 25, 1975

234,386

STORAGE UNIT

Ronald R. Hodges, Grandville, and Jack Hockenberry,
Grand Rapids, Mich., assignors to Steelcase Inc.,
Grand Rapids, Mich.

Filed May 22, 1973, Ser. No. 362,859

Term of patent 14 years

Int. Cl. D6—04

U.S. Cl. D6—159

FIG. 1

FIG. 2

FIG. 3

FIG. 4

FIG. 5

FIG. 6

FIG. 7

FIG. 8

FIG. 1 is a perspective view of a storage unit embodying the design of the invention;

FIG. 2 is a front elevational view of the storage unit;

FIG. 3 is an end elevational view of the storage unit;

FIG. 4 is a rear elevational view of the storage unit;

FIG. 5 is a top plan view of the storage unit;

FIG. 6 is a cross-sectional view taken along plane VI—VI of FIG. 2;

FIG. 7 is a perspective view of an alternative embodiment storage unit embodying the design of the invention; and

FIG. 8 is a perspective view of an alternative embodiment storage unit embodying the design of the invention.

We claim:

The ornamental design for a storage unit, substantially as shown.
